(57) **CLAIM**

We claim the ornamental design for a portable multi-tool, as shown and described.

DESCRIPTION

FIG. 1 is a front perspective view of a portable multi-tool showing our new design;

FIG. 2 is a rear perspective view thereof;

FIG. 3 is another front perspective view thereof;

FIG. 4 is another rear perspective view thereof;

FIG. 5 is an exploded front perspective view thereof;

FIG. 6 is an exploded rear perspective view thereof;

FIG. 7 is another exploded front perspective view thereof;

FIG. 8 is another exploded rear perspective view thereof;

FIG. 9 is a front view thereof;

FIG. 10 is a back view thereof;

FIG. 11 is a right side view thereof;

FIG. 12 is a left side view thereof;

FIG. 14 is a top view thereof; and,

FIG. 14 is a bottom view thereof.

The dashed lines in the drawings illustrate portions of the portable multi-tool that form no part of the claimed design.
